UNITED STATES PATENT OFFICE.

EDWARD HUBER, OF MARION, OHIO.

REVERSIBLE LINK-MOTION.

SPECIFICATION forming part of Letters Patent No. 257,710, dated May 9, 1882.

Application filed February 10, 1882. (No model.)

To all whom it may concern:

Be it known that I, EDWARD HUBER, of Marion, in the county of Marion, and in the State of Ohio, have invented certain new and useful Improvements in Reversible Link-Motions; and I do hereby declare that the following is a full, clear, and exact description thereof, reference being had to the accompanying drawings, and to the letters of reference marked 10 thereon, making a part of this specification.

This invention relates to improvements on link-motions or reversing-links which are especially designed for use on locomotives, traction-engines, and other similar engines 15 for reversing the same or rendering the valve inactive, as may be desired.

The nature of my invention consists mainly in the combination of a segmental toothed rack, a link, and a pinion which is supported on 20 the frame of the valve rock-arm; also, in combining with the above-stated elements a shaft which is free to move endwise through the pinion-shaft, and which is provided with a lever having a latching device for engaging with 25 notches formed in a dial or stationary circular flange, as will be hereinafter explained.

In the annexed drawings, Figure 1 is an elevation of one side of my improved reversing link-motion. Fig. 2 is an elevation of the opposite side thereof. Fig. 3 is a horizontal section in the plane $x-x$ on Figs. 1 and 2. Fig. 4 is a vertical transverse section in the plane $y-y$, Figs. 1 and 2. Fig. 5 is a modification of the devices for operating the pinion and link.

35 The following description of my invention, when taken in connection with the annexed drawings, will enable others skilled in the art to understand it.

A designates a horizontal shaft or axle provided with suitable journal-boxes, and having suitably applied to it two eccentrics, which are set on their axle or shaft, as shown in Fig. 40. These eccentrics B B' are loosely embraced by the yoked ends of rods C C', the opposite 45 ends of which are connected to the upper and lower ends of a segment-shaped link, D, by means of pivot-pins $a-a$. (Shown in Fig. 1.) This link D is slotted longitudinally, and it receives in its slot a block, E, which serves as its guide, 50 and which oscillates on a short pin, e, that is rigidly secured to the arm b of an oscillating

stirrup-shaped frame, F, as shown in Fig. 2. This frame F forms part of a rock-shaft, G, which is journaled in suitable bearings on the locomotive-frame, and which has keyed or 55 formed on one end the valve rock-arm H.

J designates a segment, which is rigidly secured on one side of the slotted link D, and which has rack-teeth d formed on its exposed face and arranged in the arc of a circle having 60 the same center as the link D.

It will be seen that when the segment is on the center, as shown in Figs. 1 and 2, the valve rock-arm H will not receive motion from the shaft A, and hence the valve will be inactive, 65 and that in proportion as the link is raised above said center the valve will cut off faster. It will also be understood that when the link is depressed below said dead-center the motion of the valve will be reversed.

70 On one end of the rock-shaft G is keyed rigidly an arm, K, having a large eye-bearing, K', in its upper part, in which is suitably applied another ring, L, that affords a bearing for the square portion of the rod M. On this rod M is applied a pinion spur-wheel, N, through the hub of which and the bearing-ring L the square part of the rod M can move endwise, but not turn. The teeth of pinion-wheel N engage with the rack-teeth d on the side of 80 the segment J, which is secured to the link D. The rod M is supported near its outer end by a bearing centrally arranged with respect to a circular dial or flange, O, which is suitably secured to the frame of the locomotive, and 85 which is provided with numerous notches, e, in its edge, located at certain determined points.

An arm, P, is keyed on the shaft M and provided with a latching device, g, for engaging it with any one of the notches e, according to 90 the position in which it is desired to adjust the throw of the valve, to cut off or reverse, or, to remain inactive.

It will be seen from the above description that by my invention there can be no slip in 95 the block, as the link is always suspended by the cogs of the pinion and rack opposite the same point as the block is sustained on the pin e.

Fig. 5 shows a modification of the means 100 above described for moving the pinion N. This consists in having beveled teeth h on one side

of said pinion, and engaging therewith a bevelled spur-wheel, *i*, which receives rotation in either direction from a rack-bar, *j*, by means of intermediate spur-wheel, *k*. The rack-bar *j* is reciprocated by means of the hand-lever *S*. In this Fig. 5, *D* designates the link, *J* the rack-plate secured thereto, *F* the oscillating frame, and *K* the bearing-arm.

The main frame of the engine, to which the apparatus will be applied, is not represented in the drawings. The rack and its link are secured together, and are applied on a block, *E*, (see Fig. 3,) which is free to oscillate on a pin, *c*. This pin is rigidly secured to the arm *b* of the frame *F*. The pinion *N* also has its bearing on a shaft which is supported by an arm secured to the said frame *F*. It will thus be seen that the link and its rack and the pinion are between two arms of the oscillating frame *F*, which arms will keep the rack and pinion engaged. The thickness of the teeth of the pinion is such that sufficient play is allowed between these teeth and those of the rack to allow the required oscillation of the link.

Having described my invention, I claim—
1. The combination of the slotted adjustable link *D*, receiving motion from eccentrics

on a shaft or axle, the toothed rack applied rigidly to the link, and a pinion having its bearing on the rock-arm frame, substantially as described.

2. The combination of the frame *F*, adapted to rock in suitable bearings, the valve rock-arm *H* on this frame, the block *E*, oscillating on the pin *c* on the arm *b* of said frame *F*, the vertically-adjustable link receiving oscillation from eccentrics on a shaft or axle, *A*, the toothed segment *J*, the pinion *N*, the bearing-arm *K*, and means, substantially as described, for turning said pinion and sustaining the link at any desired point of adjustment.

3. The oscillating stirrup-shaped frame *F*, bearing the valve rock-arm *H*, the block *E*, and the arm *K*, in combination with the rack-plate *J*, the pinion *N*, means for turning this pinion and locking it, and means for oscillating the link and its segment-plate, substantially as described.

In testimony whereof I affix my signature, in presence of two witnesses, this 7th day of February, 1882.

EDWARD HUBER.
